JAMES R. WEAVER, OF NORTH IRWIN, PENNSYLVANIA, ASSIGNOR TO WESTINGHOUSE ELECTRIC & MANUFACTURING COMPANY, A CORPORATION OF PENNSYLVANIA.

COIL-IRONING MACHINE.

Application filed July 14, 1923. Serial No. 651,538.

My invention relates to ironing machines, more especially to machines adapted to iron the insulating coils formed about electrical conductors such as coil members comprising the windings of dynamo-electric machines.

It is among the objects of my invention to provide a device of the above designated character which shall be of simple compact and inexpensive construction.

It is a further object of my invention to provide a device which shall be adapted to the ironing of coil cells or insulating material in an expedient and efficient manner and which shall be capable of smoothing out the irregularities and pockets produced by the winding of insulating material about the conductor members and to maintain a sliding contact of the ironing member with the coil irrespective of the contour and shape of the surface of the coil.

Coils employed in the windings of dynamo-electric machines are provided with insulating coverings usually comprising cloth or paper strips compounded with suitable insulating gums or resins which are applied either prior or subsequent to the wrapping of the material on the conductors of the coils.

Since the voltage capacity of electrical machines depends upon the quality of the insulation used, it is essential that the materials be applied in such manner as to insure uniformity and homogeneity of the insulating structure. It is also important to maintain the dimensions of the finished coils within the limits of the armature or stator slots in which they are assembled.

In the larger units designed for extremely high voltages, the windings or coils are insulated with mica lamina, united with shellac or other binding material in sheet form, wrapped around the conductor member and then provided with a protective surface sheeting of cloth or other fibrous material. The assembled materials are subjected to heat and pressure to harden the binder to provide a mechanically strong and electrically efficient insulation. These coils are sometimes several inches in cross-section and it is difficult to properly apply the insulating material thereon as it has a tendency to become wavy and porous.

My present invention is directed to a machine adapted to iron the insulating ma-

terial on the conductor body after assembling, to solidify the binder to provide a homogeneous structure and to bring the assembled coil to the stage where it is ready to be molded to its final shape.

In the accompanying drawings constituting a part hereof and in which like reference characters designate like parts:

Fig. 1 is a side elevational view of a coil ironing machine embodying the principles of my invention,

Fig. 2 is an end elevational view thereof,

Fig. 3 is a transverse sectional view of one of the platen-carrying brackets of the machine, taken along the line III—III of Fig. 1,

Fig. 4 is a transverse sectional view of the central bracket, taken along the line IV—IV of Fig. 1, and

Fig. 5 is a cross-sectional view of a coil member illustrating a plurality of conductors having insulating material wound thereon.

Referring to Fig. 1, the device comprises a bed 1 supported by a plurality of vertical pedestals 2 and provided with end brackets 3 which are adapted to rotatably mount a plurality of drive shafts 4 connected by a worm gear drive 5 to a motor 6 mounted underneath the bed 1. A plurality of supporting brackets 7 extending vertically on the bed 1 are secured thereto and rotatable heads 8 having central openings 9 and radial openings 10 are mounted in the bracket 7. The heads 8 are provided on their outer peripheries with gear teeth 11 which are adapted to cooperatively engage a plurality of pinions 12 mounted on the drive shafts 4.

A plurality of parallel shafts 15 are movably mounted in the heads 8 and are provided with segmental gears 16 adapted to engage internal gear teeth 17 provided in the inner peripheries of the heads 8. A pinion 18 adapted to engage the teeth 17 is journaled in the central head of the machines by a stub shaft 20 having a square head 21 adapted to receive a wrench by which it is manually actuated.

A plurality of bell cranks 22 are secured to the shafts 15 by keys 23 and a pair of longitudinally extending pressure platens or ironing shoes 24 are pivotally connected to the bell cranks 22 by hinge joints 25. The short ends of the bell cranks 26 are pivotally

connected to bolts 27 extending through openings provided in extending lugs 28 formed integrally with or secured to the rotatable heads 8. Coil springs 29 are disposed around the bolts 27 and screw nuts 30 are secured on the threaded ends 31 to permit adjustment of the coil springs 29. The bell cranks 22 may consist of separate levers which may be secured on the shafts 15. The 10 platens 24 are provided with heating elements which are connected to collector rings 35 associated with a suitable electrical circuit.

The tops of the brackets 7 are provided 15 with hinged portions 36 which may be opened to permit the entry of a coil 37 placed on the supports 38 secured to the bed 1. The supports 38 are provided with adjustable screw jackets 39 to provide proper seating and to 20 insure secure gripping of the coil by the clamping jaws 40.

The coil 37 usually comprises a plurality of conductor members 42, Fig. 5, having a plurality of spirally wound superposed 25 layers of insulating sheet material 43 wound thereon. The layers 43 are of any suitable insulating substance such as mica laminæ cemented together by a suitable heat hardening binder, such as shellac or a phenolic 30 condensation product.

The operation of this device is briefly as follows: The stub shaft 20 is rotated by means of a wrench causing the segment gears 16 to rotate the shaft 15 against the pressure 35 of the coil springs 29 thereby permitting the bell cranks to be moved angularly, providing a space between platens 24. The coil 37 is inserted between the platens 24 as illustrated in Figs. 1 and 2 and the pressure 40 thereon is adjusted by drawing up the nuts 30 to compress the coil springs 29. The hinged portions 36 are closed and the motor 6 is then energized, causing the drive shafts 4 to be actuated to rotate the heads 8. The 45 heating elements in the platens are simultaneously energized by connecting an electrical circuit with the collector rings 35.

As the platens 24 are rotated about the coil 37, a sliding engagement is effected 50 therebetween which smooths out the irregularities of the insulating material 43 and simultaneously compresses it. The heated platens further soften the binding material and the continuous sliding contact of the 55 platens therewith molds the insulating material about the conductor members 42 into a uniform, homogeneous structure. The continuous heating of the binding material solidifies the same, after which the coil is 60 removed from the machine and inserted while still hot in forming molds where it is finally molded to shape and permitted to cool.

As the machine is set to the proper tension for a coil of desired size, no further ad-

justments are necessary and a large production can be obtained from a single machine as the period of operation on each coil is of relatively short duration.

It will be readily understood from the above description of my invention that a coil ironing machine made in accordance therewith provides an efficient and expedient means for ironing insulating material, and the spring actuated pressure means provides a uniform sliding contact of the heatable pressure platens along all points of the coil surface whether they be traversing along the edges or the flat sides of the coil and even in rounding the corners. This feature is clearly distinctive over any prior devices used for this purpose.

Although I have described a specific embodiment of my invention, it will be obvious to those skilled in the art that modifications may be made in the details of construction without departing from the principles herein set forth. For instance, the general design of the machine, such as the rotatable supporting members, drive shafts, and actuating mechanism may be altered to adapt it for any specific application, and the levers, springs, and the method of mounting the platens may be of any suitable design to accomplish the functions herein set forth.

I claim as my invention:

1. A coil ironing machine comprising a support, means for mounting a coil thereon, a pair of heatable pressure platens for engaging said coil pivoted at diametrically opposite points and rotatably mounted on said support, pressure means for said platens comprising a plurality of coil springs and means for adjusting the pressure on said 100 platens independently of each other.

2. A coil ironing machine comprising a support, means for mounting a coil thereon, two identical heatable pressure platens for engaging said coil rotatably mounted on opposite sides of said support, means for separating said platens for the removal and insertion of a coil, pressure means for said 110 platens comprising a plurality of coil springs and means for adjusting the pressure on said platens independently of each other.

3. A coil ironing machine comprising a support, a plurality of vertical brackets mounted thereon, a plurality of shafts 120 mounted 180° apart in said brackets, a pair of cooperating pressure platens actuated through said shafts and spring pressure means for said platens comprising a plurality of independently adjustable coil springs 125 associated with the mounting brackets thereof.

4. A coil ironing machine comprising heatable platens, means for mounting a coil between the heatable platens, a plurality of 130

- rotatable supports, a pair of parallel shafts mounted diametrically opposite each other in said supports, pressure means for said platens comprising a plurality of spring actuated bell crank connections mounted on said shafts, and means for adjusting said springs to vary the pressure of said platens.
5. A coil winding machine comprising a base, a plurality of rotatable supports 10 geared to a plurality of drive shafts, a pair of shafts mounted at diametrically opposite points in said supports, bell cranks secured to said last named shafts, pressure platens hinged on one end of said cranks, adjustable 15 spring means associated with the other ends of said cranks for varying the pressure of said platens, means for separating said platens against the spring pressure and means for mounting a coil between the platens and 20 securing the same to said base.
6. A coil ironing machine comprising a base, a plurality of vertically extending guide brackets mounted thereon, a pair of drive shafts journaled therein, rotatable 25 heads mounted in said brackets, gear wheels on said drive shafts adapted to engage gear teeth provided in the outer periphery of said heads, a pair of shafts mounted diametrically opposite each other in said heads, 30 segmental gears secured on said shafts adapted to engage internal gear teeth provided in said heads, a pinion journaled in one of said heads in engagement with its internal gear teeth, a plurality of cooperating 35 arms mounted on said last mentioned shafts, a pair of heatable pressure platens hinged to said arms, extension lugs on said arms having hinged bolts thereon, coil springs on said bolts adapted to engage extensions on said heads, adjusting nuts for said springs 40 and means for mounting a coil on said base in cooperative engagement with said pressure platens.
7. A coil-ironing machine comprising a support, a plurality of vertical brackets 45 mounted thereon, rotatable heads mounted in said brackets, a pair of identical cooperating pressure platens pivoted at 180° from each other in said rotatable heads and adapted to exert pressure towards each other 50 along a line passing through the center of the rotatable heads.
8. A coil-ironing machine comprising a support, a plurality of vertical brackets 55 mounted thereon, a plurality of rotatable heads mounted in the brackets, two shafts mounted in the rotatable heads at diametrically opposite points, bell cranks secured to the shafts, and a pair of cooperating pressure platens pivotally mounted on said bell 60 cranks.
9. A coil-ironing machine comprising means for supporting a coil to be ironed, two identical pivoted pressure members disposed on opposite sides of the said coil and adapted to exert pressure upon the full length thereof, and means for rotating said pressure members around the coil to be ironed.
- In testimony whereof, I have hereunto 65 subscribed my name this 11th day of July, 70 1923.

JAMES R. WEAVER.
